UNITED STATES PATENT OFFICE.

WILLIAM T. HIGHT, OF BOSTON, AND GEORGE W. HIGHT, JR., OF QUINCY, MASSACHUSETTS.

SLIDING SHOE FOR FURNITURE.

1,114,353.

Specification of Letters Patent.

Patented Oct. 20, 1914.

Application filed October 16, 1912. Serial No. 726,026.

To all whom it may concern:

Be it known that we, WILLIAM T. HIGHT and GEORGE W. HIGHT, Jr., both citizens of the United States, and residents, respectively, of Boston, in the county of Suffolk and State of Massachusetts, and Quincy, in the county of Norfolk and State of Massachusetts, have invented new and useful Improvements in Sliding Shoes for Furniture, 10 of which the following is a specification.

This invention relates to shoes, casters or similar supports for furniture, and its object is to provide a shoe or base of this character which will be safeguarded against 15 breakage from the knocks or blows to which the article is likely to be subjected in use, notwithstanding the shoe may be made of fragile or brittle material.

In the accompanying drawings which 20 illustrate one embodiment of the invention, Figure 1 is a vertical central section, partly in elevation, of the device applied to the leg of a piece of furniture; Fig. 2 is a vertical central section, partly in elevation, showing 25 one form of connection between the stem and the cushion presently to be described; and Fig. 3 is a plan view of the shoe shown in Fig. 1.

In furniture shoes made of fragile material, such as glass, rigidly and inflexibly secured to the article of furniture resting thereon, it frequently happens that a lateral knock or blow on the unyielding shoe, or a blow on the bottom due to bringing the piece 35 of furniture too forcibly down on the floor, will break or crack the shoe, and the principal object of our invention is to obviate this danger. To this end we connect the shoe and the fitting by which the device is 40 fastened to the article of furniture by a yielding or elastic cushion, which will take up the shock of a blow in any direction on the shoe, and allow the shoe to yield sufficiently under such knocks as it is likely to 45 receive to avoid breaking the shoe.

Referring to the accompanying drawings, 50 *a* represents a glass furniture shoe or floor slide, which may have any desired exterior form or contour commonly found in such articles; as herein shown it is in the form of a flattened knob. In the upper side of the shoe is a cavity *a'*, which is preferably substantially hemispherical in form.

The fitting by which the shoe is attached

to the article of furniture, as herein shown, 55 consists of a metal stem *b*, the upper end of which is of the well known "grip-neck" type for engaging caster sockets of usual construction, and the lower end of which is provided with a head *b'*, which may be a washer, 60 disk, or other suitable head, fastened to the end of the stem. The shoe *a* and stem *b* are connected by a cushion *c* of rubber, rubber composition, or other yielding, elastic material. The headed end of stem *b* is preferable secured to the cushion *c* by being embedded therein, as shown in Fig. 2. The cushion *c* is substantially hemispherical in shape to conform to the cavity *a'*, and is made slightly larger in diameter than the 70 cavity, so that when forced into the cavity it will be held under compression. The tendency of the compressed rubber cushion to expand will hold the stem to the shoe by the frictional grip of the cushion upon the 75 walls of the cavity *a'*, without the use of cement or other securement. And by reason of the compression of the cushion, and its consequent power to expand, a lateral blow on the shoe *a* which might tend to separate 80 one side of the cushion from the cavity wall if the cushion were normally of the same diameter as the cavity, will not have that effect, but the cushion will expand to compensate for any slight displacement of the 85 shoe in either direction.

The leg of an article of furniture is shown at *d* to indicate the position of the device in use.

We claim:

1. A furniture support comprising a shoe provided with a hemispherical cavity on its upper side, a hemispherical cushion of yielding material normally having a larger diameter than said cavity and held in said cavity under compression, and a fitting by which the shoe may be attached to an article of furniture, having its end secured within said cushion.

2. A furniture support comprising a shoe 100 provided with a cavity in its upper side, a cushion of yielding material held wholly within said cavity, and a fitting by which the shoe may be attached to an article of furniture having a head embedded in said 105 cushion.

3. A furniture support comprising a shoe, 110 a fitting by which said shoe may be attached

100

105

to an article of furniture, and a cushion of yielding material in which one end of said fitting is embedded, seated wholly within a cavity in said shoe.

5 4. A furniture support comprising a shoe formed with a cavity in its upper side, a cushion of yielding material seated entirely within said cavity, and a fitting embedded at one end in said cushion and adapted to be

removably secured by its other end to an article of furniture.

Signed by us at Boston, Massachusetts this 14th day of October 1912.

WILLIAM T. HIGHT.
